UNITED STATES PATENT OFFICE.

CHARLES W. GREEN, OF ILION, NEW YORK, ASSIGNOR TO REMINGTON ARMS COMPANY, INC., A CORPORATION OF DELAWARE.

DESIGN FOR A COMBINED SHELF AND LIGHTING FIXTURE.

Application filed February 9, 1929. Serial No. 29,986. Term of patent 14 years.

To all whom it may concern:

Be it known that I, CHARLES W. GREEN, a citizen of the United States, residing at Ilion, in the county of Herkimer and State of New York, have invented a new, original, and ornamental Design for a Combined Shelf and Lighting Fixture, of which the following is a specification, reference being had to the accompanying drawing, forming part thereof.

The figure is a perspective view of a combined shelf and lighting fixture, showing my new design.

I claim:

The ornamental design for a combined shelf and lighting fixture, as shown.

CHARLES W. GREEN.
